ELECTRONIC OSCILLATOR-DETECTOR

William W. Hansen and Sigurd F. Varian, Garden City, and Russell H. Varian, Wantagh, N. Y., assignors to The Board of Trustees of the Leland Stanford Junior University, Stanford University, Calif., a corporate body of California

Original application July 8, 1938, Serial No. 218,064. Divided and this application October 24, 1942, Serial No. 463,290

46 Claims. (Cl. 315—6)

1

This invention relates, generally, to the generation, modulation, detection, amplification, transmission and reception of electromagnetic energy, and the invention has reference, more particularly to a novel electron discharge tube apparatus adapted for such uses and operating at frequencies of the order of 10^8 or more cycles per second. The present application is a true division of application Serial No. 218,064, filed July 8, 1938, now Patent No. 2,406,370, issued August 27, 1946.

In the above copending application there are described a number of embodiments of related inventions which have come to be known by the names, "rhumbatron," "klystron," "buncher," and "catcher." These names are used in the present specification. They may be defined as follows: "Rhumbatron," i. e., a resonant circuit characterized by an electromagnetic field bounded by a substantially closed conducting member, i. e., a cavity resonator, and in which energy is transferred to or from the electromagnetic field by inductive loops or capacitive elements in the field or by a beam of electrons projected through the field. "Klystron," i. e., an ultra high frequency electrical apparatus composed of one or more "rhumbatrons," i. e., cavity resonators, excited and coupled by a beam of electrons projected through the fields contained in the resonators. "Buncher," i. e., the cavity resonator in a multi-resonator "klystron" nearest the emitter of the electron beam, in which the electrons are alternately accelerated and decelerated at the frequency of oscillation of the "klystron." "Catcher," i. e., the cavity resonator in a "klystron" farthest from the emitter of the electron beam, in which energy of the "bunched" electron beam is converted into electromagnetic field energy.

The principal object of the present invention is to provide a novel electronic oscillator-detector adapted for generating, transmitting, receiving, and detecting high frequency signals.

A further object of the present invention is to provide improved electron discharge apparatus in which an electron beam is projected through a cavity resonator and is then reversed to re-enter the resonator for a further exchange of energy therewith.

Another object of the present invention is to provide improved electron discharge apparatus in which an electron beam is projected through a cavity resonator, a part of the electrons being reversed to re-enter the resonator and the re-

2

mainder being projected further and being thereafter usefully employed.

A still further object of the invention is to produce methods and means for detecting objects at a distance by the transmission and reception of radio waves intercepted by such objects.

Other objects and advantages will become apparent from the specification, taken in connection with the accompanying drawings wherein 10 the invention is embodied in concrete form.

In the drawings,

Fig. 1 is a diagrammatic representation of a device using two separate electron beams and useful in explaining the present invention. The device of Fig. 1 is claimed in U. S. Patent No. 2,406,370 granted August 27, 1946.

Fig. 2 is a diagram of the present invention having properties similar to those of Fig. 1, but with two concentric electron beams for excitation.

Fig. 3 is a curve representing the performance of the apparatus of the present invention.

Similar characters of reference are used in all of the above figures to indicate corresponding parts.

25 Referring now to Fig. 1, there are four resonant circuit members or cavity resonators 1, 2, 3, and 4 of the type shown in copending application Serial No. 214,452, filed June 18, 1938, in the name of W. W. Hansen and S. F. Varian, now Patent

30 No. 2,242,249, issued May 20, 1941. Circuit members 1 and 2 together with circuit members 3 and 4 and their associated apparatus comprise two inter-coupled velocity grouped electronic circuit means the principles of operation of which

35 are described in copending application Serial No. 168,355 filed October 11, 1937, in the name of R. H. Varian, now Patent No. 2,242,275, granted May 20, 1941. In the first unit comprising circuit members 1 and 2 there is an electron emitter

40 5 such as an activated oxide surface heated by a filament 6. The emitter 5 is connected with a battery 7 for accelerating the electrons from emitter 5 into the system. Circuit member 1 is provided with a pair of spaced grids 8 and 9

45 and two coupling loops 11 and 12. Loop 11 is connected to a line 13 for coupling to circuit member 2, and loop 12 is used for coupling into circuit member 4. Members 1 and 2 are also shown provided with coupling loops 10 and 10'

50 and connected antennae 10'' and 10'''. Openings 20 and 20' may be used with or in lieu of antennae 10'' and 10''' for receiving and radiating energy. Member 2 has a pair of spaced grids 14 and 15, and two coupling loops 16 and 55 17. Loop 16 is connected to line 13 for coupling

into resonant circuit member 1, and loop 17 is used to couple member 2 to member 3.

On the exterior of member 2 there is shown a novel detector arrangement which resembles in part the detector arrangement shown in Serial No. 185,382 now Patent No. 2,415,094, issued February 4, 1947, but which has certain advantages over that arrangement. In the present arrangement, two spaced grids 21 and 22 are placed near the grid 15 but at an angle with respect to the latter. A plate 23 is placed near the grid 22 on the side opposite grid 15. A second plate 24 is placed as indicated about at right angles to the surface of grid 15. The surface of plate 24 is provided with fins 25 or other means for preventing secondary electron emission from plate 24. Plates 23 and 24 are connected to a push-pull transformer 26 which delivers its output to a telephone or other receiver 27. Between the emitter 5 and the grid 8 there is located a control grid 37 connected to an oscillator 39 of comparatively low frequency. Between resonators 1 and 2 there is a tube 38 connected to a second low frequency oscillator 39'.

Circuit members 3 and 4 are arranged similarly to circuit members 1 and 2, respectively. Member 3 has a pair of spaced grids 28 and 29 and a coupling loop 31. An electron emitter 32 and a battery 33 correspond to similar elements of circuit member 1. Circuit member 4 has spaced grids 34 and 35 and a coupling loop 36.

The system shown in Fig. 1 may be operated in either of two ways. The simpler way is to omit resonators 3 and 4 and to operate the rest of the apparatus as a complete system within itself. A second way is more complicated, and also includes the use of resonators 3 and 4 and their effects. The operation taking place when omitting members 3 and 4 being the simpler, will now be described. In this operation of the system the electrons of the beam in passing through the grids of resonant circuit member 1 are alternately accelerated and decelerated as explained in Serial No. 168,355 now Patent No. 2,242,275, issued May 20, 1941. As a result of the changes in velocities of the electrons of the beam they arrive at the grid 14 of member 2 in groups or bunches distributed in time at the frequency of the oscillation of the system. Energy is taken from the electrons by the field of member 2 and this member is thereby excited to a state of oscillation. Energy of oscillation is transmitted from circuit member 2 to member 1 through coupling loop 16, transmission line 13, and coupling loop 11. Thus, the field of member 1 is maintained in a state of oscillation and the electron beam is accordingly acted upon and "bunched."

Radiation from the fields of both circuit members 1 and 2 or from either one is possible. Likewise, energy can be received by either one. The resonator or circuit member 2 has stronger oscillations in it than has the resonator 1, and consequently radiation from member 2 is of greater intensity than that from member 1. Conversely, reception is more favorable in member 1 than in member 2 because a signal entering 1 is amplified by the bunching effect and appears with greater intensity at member 2 than a signal introduced directly into 2. Inasmuch as reception is better performed in member 1, and transmission better performed in member 2, radiating elements such as either loops 10 and 10' or holes 20 and 20' or both may be used in the members 1 and 2.

Assuming that a modulated carrier frequency is received by member 1 through either hole 20 or antenna 10' then, the electrons of the beam

travel through grids 14 and 15 of member 2 and encounter grids 21 and 22. The electrons emerging from grid 15 have varying velocities depending upon the strength of oscillation in the circuit members 1 and 2. Some of the electrons pass through grids 21 and 22 and hit plate 23. Other electrons, i. e. the slower ones, are reflected from grids 21 and 22 to plate 24. The two grids 21 and 22 are parallel and close together. A potential difference, with grid 22 negative, is established between grids 21 and 22 by the battery 30. The resultant field between grids 21 and 22 acts like a flat mirror insofar as the slower electrons leaving grid 15 are concerned. These electrons enter the field between grids 21 and 22 and their motion is opposed by this field and they are deflected toward plate 24. The faster electrons are deflected, or rather, refracted, but they penetrate the field between grids 21 and 22 and hit plate 23. The slower electrons are not able to penetrate the field between grids 21 and 22 and they bounce to the left as in ordinary optical reflection from grid 21 to hit plate 24. In the structure constituted by members 1 and 2, all the electrons leaving the grid 15 have substantially the same velocity when the system is not oscillating. As the amplitude of oscillation increases, the electrons vary in velocity, the extremes of velocity being the greater, the greater the amplitude of oscillation. The potential difference between grids 21 and 22 is adjusted either so that most of the electrons are reflected toward plate 24, or so that most of them are permitted to pass through to plate 23. The precise difference of potential between grids 21 and 22 giving the most sensitive or the most efficient detector action as may be preferred can be found by experimental adjustment of battery 30. The detector characteristic of this system is analogous to that found in ordinary vacuum tube circuits. Since practically all the electrons emerging from grid 15 eventually strike either plate 23 or plate 24 any increase in current reaching one of the plates is accompanied by a decrease in current reaching the other plate. Hence, the current produced by electrons reaching plate 23 is 180 electrical degrees out of phase with current produced by electrons reaching plate 24, and accordingly the currents from plates 23 and 24 are appropriate to the operation of any push-pull apparatus, such as transformer 26 and receiver 27, usually used with push-pull detectors. Hence, the received signal is heard at phone 27.

The grid 31 and the tube 38 and the oscillators 39 and 39' are used to control the operation of the system as by producing modulation or for starting and stopping oscillation. The actions of grids in the location of grid 37 and tubes in the location of tube 38 have been described in Serial Nos. 185,382 and 201,898 now Patent No. 2,280,824, issued April 28, 1942. The action of these elements can be summarized by mentioning that an alternating voltage applied to grid 37 or to tube 38 accomplishes amplitude modulation with some frequency modulation. Also, in the use of grid 37 and tube 38 if the voltage is made sufficiently high the oscillation of the system can be stopped during part of every modulating cycle. The frequency of oscillators 39 and 39' may be any desired up to about 10^7 cycles per second, or even more if the frequency of the circuit members 1 and 2 is higher than 10^8 or 10^9 cycles per second. Ordinarily, the frequencies of oscillators 39 and 39' will be well within the fre-

quency range of ordinary triode oscillators. Either grid 37 or tube 38 or both may be used. Ordinarily only one will be required, although in some instances it will be convenient to use both operating at different frequencies.

The assemblage shown in the figure will operate as a simple "klystron" for transmission of radio waves or for the detection thereof or both. It will also operate as a modulated oscillator-transmitter or as a superregenerative receiver. In one specialized application of the system it is set up as a transmitter-detector. For best results the assemblage is placed in a suitable parabolic or other reflector as described in Serial No. 185,382. The system is adjusted for sensitivity in either of two modes of operation. Either the electron accelerating voltage of battery 7 is set so that the phase of arrival of electrons in the circuit member 2 is such as to give maximum oscillation, and the coupling is reduced by adjusting loops 11 and 16 sufficiently so the oscillator will barely oscillate, or the electron accelerating voltage is set so that the phase of arrival of the bunches in the circuit member 2 departs considerably from that which gives maximum oscillation, and the electron current or coupling 11-16 or electron accelerating voltage is adjusted just to sustain oscillation. Experiments indicate that the latter mode of operation is the more sensitive. Under these conditions of oscillation, radiation leaving the system by way of antenna 10" or hole 20' can return by reflection from a distant object and re-enter member 1. The returned radiation will produce a field in member 1 which may have any possible phase difference relative to the "bunching" field therein. The returned radiation will be amplified by bunching in member 1, "catching" in member 2, and feed-back into member 1 in a manner analogous to that in a regenerative detector. The amplified signal will combine with the steady oscillation of the system and it will add to or subtract from the steady oscillation depending on the relative phase of the received signal and the steady oscillation of the system. The observed result of the action of the system will be to receive at receiver 27 a signal of undulating intensity as the distance from circuit member 1 to the outside reflector or object varies. The variation in distance will cause a corresponding variation in phase of the received signal.

In the operation of the system as described above in which the adjustment is critically made, the reception of energy at the frequency of the transmitted energy, that is, the reception of energy transmitted and reflected back to the system, has the same effect as if the rate of energy loss were changed by any other cause. The effect is the same as if the radiation resistance were changed, and insofar as an analysis of operation of the system is concerned, the reflector or object outside which returns radiation to the system is in effect part of the system. Accordingly, it is convenient to consider the combined effects of transmission and reception as if the variation in resultant detected signal were the effect of variation of radiation resistance.

In these methods of operation grid 37, tube 38 and oscillators 39 and 39' are not used.

Another way of operating the system is to use either grid 37 or tube 38 with one of their oscillators 39 or 39' adjusted so that during part of the low frequency oscillation cycle the system will oscillate strongly and during another part of the cycle the same will oscillate weakly. It is

characteristic of "klystrons" that they are comparatively sensitive to the effects of incoming signals when they are oscillating weakly but relatively insensitive when oscillating strongly. For effective radiation strong oscillations are desired. The adjustment of voltage on grid 37 or tube 38, whichever is used, is such as may be required to nearly stop oscillations during part of each low frequency cycle. During other parts of the cycle the system can operate with less restriction and at some parts of the cycle without any restriction.

Thus, the system transmits pulses of high frequency radiation, the pulses being at the frequency of the low frequency oscillators 39 or 39', and in between pulses of radiation the system is prepared to receive radiation. If the transmitted radiation encounters a suitable reflecting body or object some radiation will be returned to the system where it will be received and detected during the reception part of the low frequency cycle. In this mode of operation, the system operates alternately as a detector and as an oscillator. Furthermore, it may operate as a superregenerative detector if adjusted properly. The conditions for superregeneration are, in general, fulfilled if the oscillator is allowed repeatedly to build up self-sustained oscillations for a period shorter than the time required for the oscillator to reach full oscillation, and then is stopped. The amplitude reached before oscillation is stopped is then sensitive to incoming signals.

Thus, it will be evident by reference to Serial No. 185,382 that the system described herein is applicable to the uses described in that application. In general, the present invention can be used in many applications such as location of remote objects requiring an oscillator transmitter and receiver detector operating either simultaneously or alternately. When using this apparatus for the purpose of locating remote objects a shield 4' would ordinarily be used between the transmitter antenna 10" and the receiver antenna 10'.

The operation of the system shown in Fig. 1 including use of circuit members 3 and 4 resembles that described when using members 1 and 2 alone, but the use of 3 and 4 provides a novel type of control for members 1 and 2. This novel type of control accomplishes, in effect, feed-back from circuit member 2 to circuit member 1 which is non-linear, that is, feed-back in which the transfer of energy is not proportional to the energy in the primary circuit. The use of this type of feed-back enables the "klystron" to operate efficiently as an oscillator and as a detector at the same time, as will further appear.

For sensitivity in detection as an oscillator-detector the mutual conductance of the circuit should be substantially constant. The mutual conductance is the ratio of the change in output load current of the system to the change in input control voltage of the system. In the ordinary "klystron," the mutual conductance is constant at small amplitudes of oscillation, and then gradually decreases at large amplitudes of oscillation. This is indicated in Fig. 3 in which the mutual conductance of a circuit is indicated as ordinates and the amplitude of oscillation as abscissae. In this figure there are three curves drawn, one showing mutual conductance as a function of amplitude in a "klystron" with ordinary or normal excitation, a second curve showing mutual conductance as a function of amplitude in a "klystron" with "over-bunched" excitation, and

a third curve showing the operation of a "klystron" with a combination of normal feed-back and feed-back through an over-bunched "klystron." In the curve showing operation with this combined form of excitation conforming to Fig. 1 when resonators 3 and 4 are used, there is a region in which the mutual conductance is substantially constant over a considerable range of amplitudes. This is indicated on the curve by the expression "operating region."

For quantitative examination of the operation of the "klystron" an expression for mutual conductance (G_m) is stated as follows:

$$G_m = \frac{I_0}{V_0} \frac{2\pi L}{B\lambda} \frac{J_1(x)}{x}$$

where

$$x = \frac{\pi L}{\beta \lambda V_0} V_1$$

I_0 = current in the electron beam,

L = bunching distance which in Fig. 1 is the distance between grid 9 and grid 14,

V_0 = voltage, in Fig. 1 of battery 1,

V_1 = the effective high frequency voltage between the buncher grids,

β = The ratio of electron velocity in the electron beam to the velocity of light,

λ = wave length, and

J_1 = the Bessel function of order 1. Any convenient consistent system of units can be used in the above expressions.

For small values of x in an ordinary "klystron,"

$$\frac{J_1(x)}{x} = \frac{1}{2}$$

and as x increases, G_m decreases, passing through zero and oscillating as indicated in Fig. 3. With variation of amplitudes of oscillation, the mutual conductance varies, according to an oscillating curve which is not constant for any appreciable part of its length except where x is close to zero.

It is only when operating with the mutual conductance very nearly constant that a small change in radiation resistance of the radiator can produce a large relative change in amplitude of oscillation, but if a large absolute change of amplitude is desired, as well as a large relative change, the oscillator must have a large amplitude of oscillation. In the ordinary "klystron," the mutual conductance is not constant when the amplitude of oscillation is large, hence we may have a large relative change of amplitude with the "klystron" operating at small amplitude of oscillation or we may have a small relative change of amplitude with the "klystron" operating at large amplitude of oscillation. In the present invention there are means for producing both a large amplitude of oscillation of the "klystron" and a large proportionate change in amplitude as a function of radiation resistance at one and the same time. Under special conditions as represented in Fig. 3 by the curve marked "over-bunched" excitation, the mutual conductance can either decrease or increase with change in amplitude depending on the degree of bunching. These conditions are produced in the arrangement shown in Fig. 1.

Circuit members 1 and 2 and the elements associated with them are operated as described before substantially like an ordinary "klystron." Resonators 3 and 4 operate substantially like an ordinary "klystron" except that the amplitude of oscillation in member 3 is greater than is usual

in the "buncher" of a "klystron." This is obtained by adjusting the coupling 17-31. That is, the amplitude of oscillation in member 3 is greater than the normal amplitude used in member 1.

The greater than usual amplitude of oscillation in member 3 produces a greater than usual alternating field between grids 28 and 29. This field imparts larger than usual changes in velocity to the electrons drawn from emitter 32 through grids 28 and 29. The result is that the electrons after leaving grid 29 become bunched to the optimum degree sooner in their transit toward grid 34 than they would with normal excitation, and by the time they reach grid 34 they have already passed through a condition in which they would extract energy from a "catcher" circuit, and are progressing toward a second bunched condition in which they would deliver energy when they reach resonator 4.

Now in the curves of Fig. 3 if an amplitude of oscillation is selected in which the mutual conductance of the normal "klystron," 1-2, is decreasing, and the excitation of member 3 is adjusted so the mutual conductance at the same amplitude is increasing, anything that occurs in the system to change amplitude will cause the mutual conductance associated with the "klystron" 1-2 and the electron beam thereof to change in the opposite way from the mutual conductance associated with the "klystron" 3-4 and the electron beam thereof. That is, when the mutual conductance of members 1 and 2 increases, the mutual conductance at members 3 and 4 decreases and vice versa. The resultant effect is that over a portion of the operating range of amplitudes of the system, the mutual conductance of the system is substantially constant.

Under these conditions of operation the system can oscillate and radiate at a comparatively high power output, and at the same time be sensitively responsive to an incoming signal or to a change in radiation resistance. In such a mode of operation the arrangement shown in Fig. 1 may be placed relative to a parabolic reflector as described in Serial No. 185,382 with the antenna 10" connected to coupling loop 10 or the opening 20 facing the mirror at the mirror focus, or it may radiate without the aid of any other apparatus. If the transmitted beam goes out into uninterrupted space the system will oscillate and radiate stably. Suitable reflectors are also shown in Figs. 7 and 8 of said Patent No. 2,406,370.

If while the system is radiating, a reflecting surface is placed to intercept the transmitted beam, some radiation may be reflected back into the circuit member 1 either through coupling loop 10 or opening 20. This returned energy either adds to or subtracts from the energy in member 1 depending upon its phase. If, for example, it adds to the energy of member 1, bunching increases and the amplitude of oscillation increases. This causes circuit member 2 to oscillate at greater amplitude, and to excite member 3 more strongly. Circuit member 3 bunches the beam traversing grids 28 and 29 to a greater extent than before and this correspondingly affects circuit member 4 which finally reacts on member 1 through 36-12. Referring again to Fig. 3, it will be seen that the increase of amplitude of oscillation in members 1 and 2 results in a decrease of mutual conductance, whereas the increase of amplitude in members 3 and 4 results in an increase of mutual conductance. The combined effect of these changes is to retain for the system a substantially unchanged mutual conductance over a

limited zone as indicated by the substantially horizontal portion of the curve shown in dash lines.

This system under the conditions described is, in the region specified, stably sensitive to received radiation, to which it responds depending on the magnitude and phase of the received signals. The responses of the apparatus to the received signal are detected, in the electron beam emerging from grid 45, by the elements numbered 21 to 27 inclusive. The particular arrangement for detection shown in Fig. 1 is only one of several that can be used. Other detection arrangements have been disclosed in Serial Nos. 185,382, 193,268, now Patent No. 2,272,165, issued February 3, 1942, and 201,898.

The general principles involved in the operation of the embodiment of this invention shown in Fig. 1 are applied also in a second embodiment shown in Fig. 2. In Fig. 2 only two circuit members 1' and 2' are employed. Members 1' and 2' have the same grids, coupling loops, and other appurtenances as in the structure of Fig. 1 except those associated also with circuit members 3 and 4 of that figure which of course are not required. In Fig. 2 two electron emitters 5 and 41 are used. Emitter 5 is similar to the corresponding emitter of Fig. 1, but is made somewhat smaller in proportion to the size of grids 8 and 9. Emitter 41 is of annular form concentric with and surrounding emitter 5. Two grids 42 and 43 are provided in front of emitter 5 for the control of the shape of the field in the immediate vicinity of emitter 5. Two other grids 44 and 45 are provided at the adjacent surfaces, as shown, of circuit members 1' and 2'. Grid 44 is connected to member 1' while grid 45 is insulated from member 2' although supported thereon. Grids 42 and 43 are connected to emitter 41 and are maintained at a potential which is positive with respect to emitter 5. Grid 45 is positive with respect to emitter 5 and negative with respect to emitter 41.

In the operation of the structure of Fig. 2, electrons from emitter 5 are formed as a cylindrical beam 46 projected along the axis of the system. This beam of electrons passes through resonant circuit members 1' and 2' as usual in the "klystron" providing excitation for member 2' feeding back through interconnected loops 16 and 11 to member 1'. Electrons from emitter 41 are formed as a beam 47 of annular cross section surrounding beam 46 and coaxial therewith. The electrons of beam 47 pass through member 1' and are bunched as usual, but they do not enter circuit member 2'. Instead they are reversed in transit between grids 44 and 45 by the action of the latter grid, and they are projected back through grids 9 and 8. The reversal of the electrons of beam 47 between grids 44 and 45 is, of course, the consequence of having grid 45 negative with respect to the emitter 41. The reversal of the electrons of beam 47 is illustrated in Fig. 2 by the doubling back of the boundary lines of beam 47, as indicated by the lines 48. These electrons of beam 47 are acted upon for bunching by member 1' when they pass initially through grids 8 and 9 in their travel toward grid 44, and the bunching process continues during the time the electrons travel from grid 9 through grid 44 toward grid 45 and then back to grid 9. The energy of the bunched electrons of beam 47 acts upon the field of 1', these electrons being in an overbunched condition such that the mutual conductance contributed by this beam is increasing with increasing amplitude.

The operation of Fig. 2 in combined transmission and reception is similar to that of Fig. 1 as explained before with reference to Fig. 3. The characteristic of ordinary excitation shown in Fig. 3 is obtained by the action of the beam 46 from the emitter 5, and the characteristic of overbunched excitation is obtained by the action of the beam 47 from the emitter 41. The combined action of these two beams gives the combined excitation characteristic shown in dash lines in Fig. 3, i. e. a region in which the mutual conductance changes but little over a definite range of amplitudes. Accordingly, Fig. 2 can be used for those operations requiring simultaneous transmission and reception of signals as described for Fig. 1, in which case the shield 4' or equivalent is employed. In Fig. 2 the elements 21 to 27 inclusive shown in Fig. 1 for signal detection have been omitted for convenience, although they would be used in the same way in Fig. 2 as in Fig. 1.

In Figs. 1 to 3, if desired, only a single radiating means supplied from either the electron grouping circuit or on the electron absorbing circuit may be used both as transmitter and receiver.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

35. 1. An electronic device comprising an apertured thermionically emitting structure, an accelerating electrode, a second thermionically emitting structure on the opposite side of said first structure from said electrode, and potential supply means coupled to said electrode and said structures for electrically biasing said first emitting structure with respect to said second emitting structure and for biasing said electrode with respect to said first structure to draw thermions from said second structure through said first structure toward said accelerating electrode and also from said first structure toward said electrode.
40. 2. An electronic device as defined in claim 1, comprising an apertured electrode positioned beyond said accelerating electrode, and means connecting said last apertured electrode to said potential supply means to bias said electrode to turn back thermions from said first emitting structure while causing thermions from said second emitting structure to continue therethrough.
45. 3. An electronic device as in claim 1, in which an apertured internally resonant hollow body is positioned beyond said accelerating electrode in the path of the thermions from both of said thermionically emitting structures, and means beyond said body for turning the thermions from said first structure back into said internally resonant hollow body after said thermions have initially passed outwardly thereof.
50. 4. An oscillator comprising means including a cathode for producing a uniform-velocity electron beam, means including a cavity resonator provided with openings in the path of said beam to permit passage of said beam therethrough for imparting velocity modulation to said beam, and means in the path of said beam beyond said resonator for producing a reversing field acting on said beam to convert its velocity modulation into 55 charge-density modulation and to return a por-
55. 5. An oscillator comprising means including a cathode for producing a uniform-velocity electron beam, means including a cavity resonator provided with openings in the path of said beam to permit passage of said beam therethrough for imparting velocity modulation to said beam, and means in the path of said beam beyond said resonator for producing a reversing field acting on said beam to convert its velocity modulation into 60 charge-density modulation and to return a por-
60. 6. An oscillator comprising means including a cathode for producing a uniform-velocity electron beam, means including a cavity resonator provided with openings in the path of said beam to permit passage of said beam therethrough for imparting velocity modulation to said beam, and means in the path of said beam beyond said resonator for producing a reversing field acting on said beam to convert its velocity modulation into 65 charge-density modulation and to return a por-
65. 7. An oscillator comprising means including a cathode for producing a uniform-velocity electron beam, means including a cavity resonator provided with openings in the path of said beam to permit passage of said beam therethrough for imparting velocity modulation to said beam, and means in the path of said beam beyond said resonator for producing a reversing field acting on said beam to convert its velocity modulation into 70 charge-density modulation and to return a por-
70. 8. An oscillator comprising means including a cathode for producing a uniform-velocity electron beam, means including a cavity resonator provided with openings in the path of said beam to permit passage of said beam therethrough for imparting velocity modulation to said beam, and means in the path of said beam beyond said resonator for producing a reversing field acting on said beam to convert its velocity modulation into 75 charge-density modulation and to return a por-

tion of the energy of the charge-density-modulated part of the beam into said resonator.

5. An oscillator comprising means for producing a substantially uniform-velocity beam of electrons, means including a cavity resonator having openings in the path of said beam to permit passage of the beam therethrough for imparting velocity modulation to the beam, and means including an electrode in the path of said beam for reversing at least the lower velocity components of the beam after its passage through said resonator and for returning the reversed components into energy-exchanging relation with said resonator.

6. High frequency electron discharge apparatus, comprising a cavity resonator having electron permeable walls and adapted to contain an oscillating electromagnetic field, means comprising a cathode on one side of said resonator and spaced therefrom for projecting electrons through said resonator whereby said electrons and said field interchange energy, and means in the path of said electrons beyond said resonator for reversing the flight of said electrons to further interchange energy with said field.

7. An oscillator comprising means including a uniform-velocity cathode for producing an electron beam, means including a cavity resonator spaced from said cathode and provided with openings in the path of said beam for imparting velocity modulation to said beam, and means along the path of said beam beyond said resonator for producing a reversing field acting on said beam to return a portion of the energy of the beam into said resonator.

8. An oscillator comprising means for producing a uniform-velocity beam of electrons, means including a cavity resonator having openings in the path of the beam for imparting velocity modulation to the beam, means along the path of said beam beyond said resonator for causing the electrons of said beam to become bunched, and means including an electrode in the path of said beam for reversing said bunched beam and for returning said beam to said resonator into energy-exchanging relation therewith, whereby oscillations are sustained in said resonator.

9. High frequency apparatus comprising a cavity resonator means adapted to contain an oscillating electromagnetic field, means aligned with said resonator for projecting an electron beam through said resonator, means along the path of said beam for returning a portion of said beam through said resonator for further interaction with said field, and means along said path comprising an additional cavity resonator means for abstracting high frequency energy from the remainder of said beam.

10. High frequency apparatus comprising means for producing an electron beam and for passing said beam through an oscillating electromagnetic field, means along the path of said beam for returning a portion of said beam for further interaction with said field after passage therethrough, and means along said path for extracting high frequency energy from the unreturned remainder of said beam.

11. High frequency apparatus comprising means including a cathode for producing a uniform-velocity electron stream, a cavity resonator in the form of a figure of revolution about a predetermined axis extending along the path of said stream, said resonator having a pair of electron-permeable walls adjacent said axis, and spaced from said cathode, and a reflector electrode in

the path of said stream beyond said resonator and spaced therefrom for returning electrons of said stream into said resonator for sustaining oscillations therein.

5 12. High frequency apparatus comprising a cavity resonator in the form of a figure of revolution about a predetermined axis, and having a pair of electron-permeable walls adjacent said axis, a cathode adjacent one of said walls and outside said resonator, and a reflector electrode adjacent the other of said walls and outside said resonator.

15 13. High frequency apparatus comprising a substantially toroidal cavity resonator having a pair of electron-permeable walls adjacent the axis thereof, a cathode opposite one of said walls and outside said resonator, and a reflector electrode opposite the other of said walls and outside said resonator.

20 14. High frequency apparatus comprising a cavity resonator in the form of a figure of revolution about a predetermined axis and having a pair of closely adjacent electron-permeable walls along said axis and forming a narrow gap therebetween, a cathode opposite one of said walls along said axis and outside said resonator, and a reflector electrode along said axis opposite the other of said walls and outside said resonator.

25 15. High frequency apparatus comprising an axially symmetrical reentrant cavity resonator having a pair of closely spaced electron-permeable walls along the axis of symmetry thereof, a cathode adjacent one of said walls outside said resonator, and a reflector electrode adjacent the other of said walls outside said resonator.

30 16. High frequency object-detecting apparatus comprising means for producing an electron stream, a cavity resonator having apertured walls in the path of said stream, means coupled to said resonator for supplying received energy thereto, a second cavity resonator spaced from said first resonator and also having apertured walls in said stream path, means coupled to said second resonator for radiating energy from said second resonator toward an object to be detected, whereby a part of said radiated energy may be reflected from said object and supplied to said first resonator, means coupling said two resonators together, said apparatus including means for maintaining substantially constant mutual conductance between said resonators to permit oscillations at high amplitude for transmission and to render said apparatus simultaneously sensitive to small received signals, said last-named means comprising a reflecting electrode between said resonators for reflecting a portion of said beam back into said first resonator in overbunched condition.

35 17. High frequency object-detecting apparatus comprising means for producing an electron stream, means in said apparatus for receiving a radiated high frequency signal, means in said apparatus responsive to said signal for periodically varying the velocity of the electrons of said stream, means in said apparatus for causing said velocity-varied stream to become bunched, means in said apparatus spaced from said velocity-varying means for extracting high frequency energy from said bunched stream, means coupling said velocity-varying means to said energy-extracting means to sustain oscillations within said energy-extracting means, means in said apparatus for radiating a portion of said extracted energy toward an object to be detected, whereby a part of said radiated energy may be reflected

from said object and received by said receiving means, and means in said apparatus for maintaining substantially constant mutual conductance between said velocity-varying means and said energy-extracting means to permit oscillation at high amplitude for producing said radiated energy and to render said apparatus simultaneously sensitive to small received signals, said last-named means comprising means for reflecting a portion of said velocity-varied beam back into said velocity-varying means in over-bunched condition.

18. High frequency apparatus comprising means for producing an electron stream, means along the path of said stream for velocity-modulating said electron stream, means along said path for extracting high frequency energy from said modulated stream, means coupling said modulating means and said extracting means together to sustain oscillations in said extracting means, said apparatus also including means for maintaining substantially constant mutual conductance between said modulating means and said extracting means, said last-named means comprising means along said path for reflecting a portion of said beam back through said velocity-modulating means in overbunched condition.

19. High frequency electron discharge apparatus comprising means for producing an electron stream, a pair of electron-permeable electrodes in the path of said stream and defining a gap therealong, tuned circuit means coupled to said electrodes for producing a high frequency alternating electric field across said gap, a further electron-permeable electrode in said path, said apparatus including means defining a field-free space between said further electrode and said gap, a reflector electrode in said path beyond said further electrode, and biasing means coupled to said reflector electrode for maintaining said reflector electrode at a negative potential with respect to said further electrode, whereby the electrons of said stream are reflected to reenter said gap and maintain said field.

20. High frequency electron discharge apparatus comprising means for producing an electron stream, means in the path of said stream for producing an axially extending alternating electric field for velocity-modulating said stream, said apparatus including means defining a field-free space surrounding the path of said stream beyond said field-producing means, and means for defining a reflecting electric field in the path of said stream adjacent to and beyond said field-free-space-defining means, whereby said electron stream is reversed to maintain said alternating field.

21. High frequency electron discharge apparatus comprising means for producing an electron stream, a cavity resonator having a pair of apertured walls in the path of said stream, an electron-permeable electrode in said path, said apparatus including means defining a field-free space between said resonator and said electrode, a reflector electrode in said path beyond said first electrode, and biasing means coupled to said reflector electrode for maintaining said reflector electrode at a negative potential with respect to said first electrode, whereby the electrons of said stream are reflected to reenter said resonator to exchange energy with the electromagnetic field therein.

22. High frequency electron discharge apparatus comprising means for producing an electron stream, a cavity resonator having electron-

permeable walls in the path of said stream, said apparatus including means defining a field-free space surrounding the path of said stream beyond said resonator, and a reflector electrode in the path of said stream beyond said field-free space for reflecting the electrons of said stream to reenter said resonator.

23. High frequency electron discharge apparatus comprising means for producing an electron stream, a cavity resonator having electron-permeable walls in the path of said stream, a reflector electrode in the path of said stream beyond said resonator for reflecting the electrons of said stream to reenter said resonator, and a further electron-permeable electrode positioned along the path of said stream between said resonator and said reflector electrode for further controlling said stream.

24. High frequency apparatus, comprising a cathode, a pair of grids and a reflector electrode, all said electrodes being aligned along an electron stream path, and means coupled to said grids and defining a cavity resonator therewith adapted to have an electric field extending along said path between said grids and spaced from said cathode and reflector.

25. Apparatus as in claim 24, further comprising potential source means coupled between said cathode and resonator for maintaining said cathode negative with respect to said resonator, whereby electrons from said cathode are accelerated toward and through said grids, and further including potential source means coupled to said reflector electrode for maintaining said reflector electrode negative with respect to said grids, whereby said electrons are repelled and reversed by said reflector electrode and caused to reenter said resonator by way of said grids.

26. Apparatus as in claim 24, further including another grid electrode between said reflector electrode and said pair of grids.

27. High frequency apparatus comprising a cathode, a reflector electrode spaced therefrom and a cavity resonator between and spaced from both said cathode and reflector electrode and adapted to sustain a high frequency electric field extending in a region between said cathode and reflector electrode upon excitation of said resonator.

28. A high frequency electronic device comprising a hollow cavity resonator capable of being energized to support high frequency electrical oscillations to produce a high frequency electric field, a source of electrons and means for causing electrons from the source to traverse at least portions of a path extending in alignment with the electron source and the resonator, the traversed portions of the path including a region occupied by the high frequency electric field and including also spaces on each side of that region which are free from the high frequency field, for permitting electrons to pass through said spaces without influencing said field, said means comprising an accelerating electrode located along the said path and so polarized as to propel electrons through the high frequency field region in the direction away from the electron source, and a retarding and reversing electrode located along the path on the side of the high frequency field region opposite the electron source and so polarized as to propel electrons through the high frequency field region in the direction toward the electron source.

29. A high frequency device comprising a hollow cavity resonator capable of being energized to

support high frequency electrical oscillations to produce a high frequency electric field, a source of electrons external to the resonator, an electron collecting electrode spaced from the electron source, the resonator being located between the electron source and the collecting electrode and having an opening in its structure such that electrons traversing the path between the electron source and the collecting electrode pass through the high frequency electric field associated with the resonator in the vicinity of the opening and through regions on each side of the high frequency field region which are free of high frequency field, an electron accelerating electrode located along the said electron path and polarized such as to propel electrons through the high frequency field in the direction away from the electron source and an electron retarding and reversing electrode located along the electron path on the side of the resonator opposite the electron source and polarized such as to propel electrons through the high frequency field in the direction toward the electron source.

30. A high frequency electronic device comprising a hollow cavity resonator capable of being energized to support high frequency electrical oscillations, a gap in the structure of the resonator such that electrons projected across the gap will pass through the high frequency electric field associated with the resonator when it is energized, a space on each side of the gap which is free from the high frequency field, a source of electrons external to the resonator, an electron accelerating electrode so positioned and polarized with respect to the electron source as to propel electrons from the source through the high frequency electric field across the said gap in the direction away from the electron source, an electron retarding and reversing electrode positioned along the path of the above-mentioned electrons on the side of the gap opposite the electron source and so polarized as to stop, reverse and propel at least some of the electrons through the high frequency field across the said gap in the direction toward the electron source, and electric potential means for polarizing the said electrodes.

31. In a high frequency amplifier, a resonant cavity input circuit, a resonant cavity output circuit, an electron emitting cathode, an electron collecting electrode spaced from the cathode, means for causing a stream of electrons to leave the cathode and traverse at least portions of the path between the cathode and the collecting electrode, the input and output resonant cavities having openings in their structures and being so placed along the electron path between the cathode and the collecting electrode that electrons from the cathode pass first through the high frequency electric field associated with the input cavity in the vicinity of the opening in that cavity then through the high frequency electric field associated with the output cavity in the vicinity of the opening in that cavity, there being also regions along the electron path on each side of the last-mentioned opening which are free of high frequency field, the said means for causing electrons to traverse the said paths comprising at least one electron accelerating electrode so polarized as to propel electrons in the direction away from the cathode through the high frequency field and the regions free of high frequency field in the vicinity of the opening in the output cavity, and at least one accelerating electrode so polarized as to propel electrons in the

direction toward the cathode through the high frequency field and high frequency field free regions in the vicinity of the opening in the output cavity, means for transferring high frequency energy from the output cavity to a utilization circuit, and means for energizing at high frequency the input cavity whereby high frequency variations are impressed upon the electron stream from the cathode as it passes through the high frequency field associated with the input cavity in the vicinity of the opening in the input cavity structure.

32. An amplifier according to claim 31 in which the means for impressing the high frequency variations upon the electron stream as it passes through the high frequency field associated with the input cavity are means for producing variations in the electron velocities.

33. An amplifier according to claim 31 in which the means for impressing the high frequency variations upon the electron stream as it passes through the high frequency field associated with the input cavity are means for producing variations in the charge density of the electron stream.

34. A high frequency electronic device, comprising a hollow cavity resonator capable of being energized to support high frequency electrical oscillations to produce a high frequency electric field, a source of electrons external to the resonator, and means for causing electrons from the source to traverse at least portions of a path extending from the source and including a region occupied by the high frequency electric field and including also spaces on each side of that region which are free from the high frequency field, said means comprising an accelerating electrode located along said path and so polarized as to propel electrons through the high frequency field region in the direction away from the source and a retarding and reversing electrode located along the path on the side of the high frequency field region opposite the electron source and polarized to repel electrons through the high frequency field region in the direction toward the electron source.

35. An amplifier comprising means for producing an electron stream, input and output circuits comprising hollow resonators having apertures to permit passage of at least portions of the electron stream through a portion of the electric field associated with the excitation energy of each of the resonators, means for exciting the input circuit whereby the interaction between the electron stream and the electric field of the input circuit resonator produces variations in the velocities of the electrons in accordance with the excitation energy, means at a point in the path of the electron stream following the place of its interaction with the field of the input circuit resonator (but in advance of the place of its interaction with the field of the output resonator) for producing a retarding field to turn back at least some of the electrons which have had their velocities reduced by the said interaction and allow other higher velocity electrons to pass on through the said portion of the electric field of the output circuit resonator and transfer energy thereto in accordance with the excitation of the input circuit resonator.

36. An amplifier comprising an input circuit an output circuit comprising a hollow electrical resonator, means for producing an electron stream, means for energizing the said input circuit, means for varying the velocities of the electrons of the said stream at a point along its course

in accord with the excitation of the input circuit, means at a subsequent point along the course of the stream for setting up a retarding electric field to turn back lower velocity electrons while allowing higher velocity electrons to pass and excite in accord with the excitation of the input circuit the hollow resonator of the output circuit which is positioned at a point still farther along the stream.

37. An amplifier including an electron emitting cathode, an electron collector, means for producing an electron stream along a path from the cathode to the collector, a resonant cavity, means comprising a pair of electrodes bounding a gap in the resonant cavity and positioned along the path of the electron stream between the cathode and the collector for varying the velocities of the electrons traversing the gap between the electrodes, a second resonant cavity, means comprising a second pair of electrodes bounding a gap in the second resonant cavity and positioned along the path of the electron stream between the first-mentioned pair of electrodes and the collector whereby density variations in the electron stream traversing the gap between the second pair of electrodes may excite electrically the second resonant cavity, and means comprising a retarding electrode positioned along the electron stream and between the two said pairs of electrodes for producing a retarding field to turn back electrons which have had their velocities reduced during traversal of the gap in the first cavity while allowing higher velocity electrons to pass on and cross the gap in the second cavity whereby the electron stream traversing the gap in the second cavity is density varied and the second resonant cavity is excited thereby in accordance with the velocity variations impressed upon the electron stream as it traverses the gap in the first resonant cavity.

38. In combination, a pair of hollow electrical resonators having apertures such that an electron stream may be projected through portions of the space of both resonators in series, means in said combination for projecting an electron stream therethrough, means external to it for exciting at high frequency the said resonator first traversed by the electron stream to produce variations in the velocities of the electrons in the stream, means in said combination for producing a retarding field located between to reduce the velocities of all of the velocity varied electrons and to turn back electrons having had a negative velocity variation permitting others to pass on into the space of the other resonator to excite it at the said high frequency, and a high frequency load circuit coupled to the said other resonator.

39. In combination, means for producing an electron stream, means for varying the velocities of the electrons of said stream, means for producing a retarding field beyond the velocity variation zone to reduce the velocities of all the electrons in the stream and to turn back electrons having had a negative velocity variation, thereby dividing the stream into two parts each having density variations in accordance with the impressed velocity variations, one part consisting of the electrons turned back by the retarding field and the other part consisting of the electrons which continue on through and past the retarding field, and a hollow resonator having an aperture in line with one of the density varied parts of the electron stream to permit the resonator to be excited thereby.

40. In combination, means for producing an

electron stream, means comprising an electrical circuit excited from a source external to it for varying the velocities of the electrons of said stream, means for producing a retarding field beyond the velocity variation zone to reduce the velocities of all the electrons in the stream and to turn back electrons having had a negative velocity variation and to pass on other electrons of said stream beyond said retarding field, thereby dividing the stream into two parts each having density variations in accordance with the impressed velocity variations, one part consisting of the electrons turned back by the retarding field and the other part consisting of the electrons which continue on through and past the retarding field, and a hollow resonator having an aperture in line with one of the density varied parts of the electron stream to permit the resonator to be excited thereby.

41. In combination, means for producing an electron stream, means in said combination for varying the velocities of the electrons of said stream, means in said combination for producing a retarding field beyond the velocity variation zone to reduce the velocities of all electrons in the stream and to turn back electrons having had a negative velocity variation and a cavity resonator beyond the zone of the retarding field having an aperture in line with the electron stream to permit the resonator to be excited by electrons which received a positive velocity variation.

42. In combination, means for producing an electron stream, means in said combination comprising an electrical circuit excited from a source external to it for varying the velocities of the electrons of said stream, means in said combination for producing a retarding field beyond the velocity variation zone to reduce the velocities of all electrons in the stream and to turn back electrons having had a negative velocity variation, and a cavity resonator beyond the zone of the retarding field having an aperture in line with the electron stream to permit the resonator to be excited by electrons which received a positive velocity variation.

43. Apparatus including means for producing an electron stream, means in said apparatus for varying the velocities of the electrons of said stream at a point along its course, means at a subsequent point along the course of the stream for setting up a retarding electric field to turn back lower velocity electrons while allowing higher velocity electrons to pass, and a cavity resonator positioned at a point still further along the course of the stream to be excited by the higher velocity electrons which succeed in passing beyond the retarding field means.

44. Apparatus including means for producing an electron stream, means in said apparatus comprising an electrical circuit excited from a source external to it for varying the velocities of the electrons of said stream at a point along its course, means at a subsequent point along the course of the stream for setting up a retarding electric field to turn back lower velocity electrons while allowing higher velocity electrons to pass, and a cavity resonator positioned at a point still further along the course of the stream to be excited by the higher velocity electrons which succeed in passing beyond the retarding field means.

45. Apparatus including means for producing an electron stream, means in said apparatus comprising a first cavity resonator adapted to be excited from a source external to it for varying

the velocities of the electrons of the said stream at a point along its course, means at a subsequent point along the course of the stream for setting up a retarding electric field to turn back lower velocity electrons while allowing higher velocity electrons to pass, and a second cavity resonator positioned at a point still further along the course of the stream to be excited by the higher velocity electrons which succeed in passing beyond the retarding field means.

46. In combination, means for producing an electron stream, means in said combination for varying the velocities of the electrons of said stream, means in said combination for producing a retarding field beyond the velocity variation zone to reduce the velocities of all electrons in the stream and to turn back only electrons having had a negative velocity variation, and a cavity resonator beyond the zone of the retarding field having an aperture in line with the path of the electron stream to permit the cavity to be excited by electrons which received a positive velocity variation.
